UNITED STATES PATENT OFFICE.

HARRIET ISABELLA SKIDMORE, OF ST. LOUIS, MISSOURI.

COLLAR-BUTTON.

1,264,697.

Specification of Letters Patent.

Patented Apr. 30, 1918.

Application filed September 14, 1916. Serial No. 120,115.

To all whom it may concern:

Be it known that I, HARRIET ISABELLA SKIDMORE, a citizen of the United States, residing at St. Louis, in the State of Missouri, have invented a new and useful Collar-Button; and I do hereby declare the following to be a full, clear, and exact description of the invention, such as will enable others skilled in the art to which it appertains to make and use the same.

This invention relates to an improved collar button, and an object of the invention is to provide a collar button having means which will slidably engage the outer wall of the elongated pocket, which is usually provided at the rear of the shirt band, so that the collar may slide backward and forward, when adjusting the same, so that its opposite ends may be connected to the front collar button.

A further object of the invention is to provide a collar button having a shank constructed from a single length of metallic wire, bent to form a substantially circular loop to engage the pocket of the shirt band, the opposite ends of the loop being twisted together and extending outwardly, upwardly and slightly inwardly toward the loop, and subsequently outwardly, to be connected to the collar button proper.

A further object of the invention is to form a substantially flat portion in the upper part of the loop, to engage the upper part of the pocket of the shirt band, to guide and hold the collar button straight or erect.

In practical fields, the details of construction may necessitate alterations falling within the scope of what is claimed.

The invention comprises further features and combination of parts, as hereinafter set forth, shown in the drawings, and claimed.

In the drawings:—

Figure 1 is a view in perspective of a portion of a shirt band, showing the collar button applied, and the collar held in place by the same.

Fig. 2 is a vertical sectional view through Fig. 1.

Fig. 3 is an enlarged detail sectional view of the collar button detached.

Referring more especially to the drawings, 1 designates a collar button shank, which is constructed from a single length of wire, which is bent to form a substantially

circular portion 2 to engage the usual pocket 3 of the rear part of the shirt band 4. This circular portion has a straight part 5 to engage the upper part of the pocket, to guide and hold the button erect. The opposite end portions of the circular portion are twisted together, as shown at 6, which part 6 extends outwardly, and passes the lower edge of the outer wall of the pocket. The end portions are further twisted together and extend upwardly and slightly inwardly toward the circular part so as to force the outer wall of the pocket slightly through the circular part, thereby holding the collar button securely in position, the parts of the upwardly and inwardly extending portion being twisted together and extending outwardly as shown at 8, at right angles to the upwardly and inwardly extending part. The parts of the portion 8, at their extremities, are welded or formed into one piece, and which piece is threaded or otherwise secured into a suitable button 9, of bone or pearl or any other suitable material. After arranging the shank in the pocket of the shirt band, and attaching the collar to the button, as shown in Fig. 1, the collar may be moved backward and forward, so that the opposite ends of the collar may be made to meet properly in front. The straight part of the circular portion prevents the shank of the collar button from leaning toward one side or the other, thereby holding the shank erect.

The invention having been set forth, what is claimed as new and useful, is:—

A collar button, formed from a single length of spring wire having a straight part midway its ends, the end portions of the wire beyond the straight part being curved in substantially circular form, thereby providing a body adapted to extend upwardly into the pocket at the rear of a shirt band, whereby said straight part is adapted to engage the upper part of a pocket to hold the circular body in position and from rocking, said end portions beyond the straight part at a point diametrically opposite said straight part being twisted together to form a rigid shank, said shank projecting outwardly from the lower part of a circular body and adapted to extend under the lower edge of the outer wall of the pocket, and upwardly and inwardly and adapted to impinge against the outer surface of the wall.

of the pocket, whereby a depression may be formed in the outer wall of the pocket below the straight part thereby holding the collar button firmly in position, the upper 5 ends of the twisted parts of said shanks extending laterally and having fixed thereto a button to engage through the button hole of a collar.

In testimony whereof I have signed my name to this specification in the presence of 10 two subscribing witnesses.

BELLE SKIDMORE.
